UNITED STATES PATENT OFFICE.

SAMUEL C. McKEOWN, OF NEWARK, NEW JERSEY, ASSIGNEE TO SPLITDORF ELECTRICAL COMPANY, OF NEWARK, NEW JERSEY.

CIRCUIT-BREAKER.

1,287,718.

Specification of Letters Patent. Patented Dec. 17, 1918.

Application filed March 15, 1917. Serial No. 155,072.

To all whom it may concern:

Be it known that I, SAMUEL C. McKEOWN, a citizen of the United States, residing at Newark, in the county of Essex and State of New Jersey, have invented certain new and useful Improvements in Circuit-Breakers, of which the following is a specification.

My invention relates to circuit breaking mechanism for the primary circuit of high tension ignition systems such as used in connection with magneto or induction coil apparatus for internal combustion engine ignition.

In particular it is devoted to means for securing a quick and effective interruption of the contact points controlling such circuit in such a way that the quick and decisive manner in which said contacts operate is not affected by slight imperfections in the manufacture of certain elements of the device, or by any unevenness or variations occurring as a result of wear.

Another object is to provide a breaker, the component parts of which may readily be disassembled to facilitate inspection or repair.

Other objects will appear from a consideration of the following description taken together with the accompanying drawing wherein reference characters are employed to identify the various parts and, Figure 1 is an end view of a high tension magneto adapted for use with a twelve cylinder engine having incorporated therein one embodiment of my invention. In this view but six of the distributor terminals are seen, the other six being in a plane behind those shown and hence not visible. Fig. 2 is a perspective showing of the rocker arm with the breaker device mounted thereon. Fig. 3 is a top view of the detachable breaker point structure seen in Fig. 1. Fig. 4 is a side elevation of the said breaker point structure. Fig. 5 is a bottom view of said breaker point structure and; Fig. 6 is a perspective view of a cam member for actuating said breaker points.

Referring to the drawings, 1 designates generally a magneto machine having a distributor head 2 provided with high tension terminal posts 3. Mounted so as to be adjustable about the shaft of the magneto 1 for the purpose of performing the usual tim-

ing function is a rocker plate 4 which has a suitable manipulating lever 5. Attached to 55 said rocker plate is a breaker mounting plate 6. Said plate 6 is fastened to the rocker plate by a plurality of screws 7 the heads of which rest in elongated holes as seen to permit of any fine adjustment between said plates that may be necessary to bring the contact points in proper relation with the shaft of the magneto. A metallic strip 8 carried by the plate 6 has mounted thereupon a U-shaped member 9 as by means 60 of screws 10. Said U-shaped member is insulated from the remaining structure by insulating layers 11 and bushings 12. A screw 13 threaded in the member 9 serves for a purpose to be described hereinafter. 70

Considering the unitary breaker point structure shown in Figs. 3 to 5, the same is seen to consist of a pair of resilient springs 14 and 15. These springs are spaced apart by an insulating block 16. Elements 75 17, 18, 19, and 20 are placed as shown and then riveted together by rivets 21 and 22. Elements 17 and 18 are metal plates which are in electrical contact with springs 15 and 14 respectively. 20 is a metal plate serving 80 as a seat against which the rivets may be headed, and to prevent said rivets from short circuiting springs 14 and 15 an insulating strip 19 is inserted between elements 18 and 20, and furthermore rivets 21 85 and 22 are preferably insulated from said springs 14 and 15 by suitable bushings. Springs 14 and 15 each has riveted thereto an extension member 23 which has its free end fashioned to receive a fiber wearing 90 piece 24. Fastened so as to be normally held flexibly in contact engagement by springs 14 and 15 are two opposing contact points 25 and 26. The element 17 has two drill holes 27 preferably located diagonally 95 thereon which are adapted to engage correspondingly situated pins 28 on strip 8 to hold the contact structure in place when assembled as shown in Fig. 1. The screw 13 may then be turned down so that its nose 100 enters the opening 35 of plate 20 and bears against the element 18 to thereby secure the structure in position.

Mounted on the magneto shaft is a cam member 29 having any suitable number of 105 actuating points 30. In the present instance

- I have shown four such points and hence to be used in connection with a twelve cylinder engine the magneto shaft must be geared to run at one and a half crank shaft speed.
- 5 The contact supporting members extend so that the cam fingers 30, which are beveled as shown at 31, pass between the wearing elements 24 to thereby force the same apart and open the breaker contacts 25 and 26.
- 10 Considering the electrical connections, current is brought from the live end of the magneto primary, in the particular type of magneto shown, by means of a conductor 32 which is clamped to a suitable lug 33 on the insulated U-shaped member 9. From here current is led by way of the clamping screw 13 to contact 25, contact 26 and thence to ground on the strip 8. Rocker plate 4 and breaker mounting plate 6 have registering notches shown at 34 to accommodate the primary conductor 32.

I am aware that the broad idea of arranging a pair of breaker points so that both are operable to simultaneously separate from each other to thereby insure a more rapid break is not new, but devices heretofore designed to operate in this manner have been subject to more or less uncertainty of action. For instance where the contacts are mounted on movable arms, spring pressed into their closing position, and a cam is adapted to separate both arms simultaneously, it is evident that should, for such reasons as wear, or imperfect manufacture, the said cam make engagement with one of said arms prior to that of the other arm the double separation action sought is defeated and in effect but one of the points make the preliminary break as in the ordinary stationary point device. By my invention I mount the contacts directly upon the resilient strips 14 and 15 so that the plane of closure of said contacts is shiftable slightly in case that a cam point 30 encounters one of the wearing elements 24 prior to the time at which it engages the other of said elements. In other words said contacts do not open until the cam is in actual engagement with both of the wearing elements, and thereby in a position to start both of the contact points in their separating movement at the same instant.

It will be apparent to those skilled in the art that various changes and alterations may be made without departing from the spirit of the present invention. Hence I do not desire to be limited to the exact details of construction shown and described herein.

Having thus described my invention what I claim is:—

- 60 1. In a device of the character described; a mounting plate; a detachable unitary contact structure located thereon; said structure including a pair of resilient spring blades, a contact point on each of said blades and

normally in closed relation with each other, 65 and wearing elements on each of said blades; a cam adapted to pass between said wearing elements to flex said blades and thereby separate said contacts; and clamping means for securing said contact structure in working 70 position on said mounting plate.

2. In a device of the character described; a mounting plate; a detachable unitary contact structure located thereon; said structure including a pair of resilient blades, a contact 75 point on each blade normally held in their closed position thereby, and a cam engaging element on each blade; a rotatable cam having fingers adapted to engage said cam engaging elements to simultaneously move said 80 contact points away from each other, and a clamping screw adapted to secure said contact structure in working position on said mounting plate.

3. In a device of the character described; 85 a mounting plate; a detachable unitary contact structure located thereon; said structure including a pair of spring blades arranged in parallel relation and insulated from each other, two opposing contact points, one on 90 each blade and normally held in closed position by the resiliency thereof; a rotatable cam adapted to act on said blades to simultaneously move said contact points away from each other; a U-shaped member at 95 attached to but insulated from said plate; and means on said member to secure said contact structure in place on said plate; said U-shaped member also serving as a portion of the electrical circuit in which one of said 100 contacts points is contained.

4. In a device of the character described, a mounting plate, a detachable unitary contact structure including a pair of spring blades each having a contact point opposing 105 each other and normally held in closure by the resiliency of said blades, a rotatable cam adapted to move each contact away from the other, the resiliency of said blades serving to permit an automatic adjustment of the plane 110 of contact of said points in order to insure that said points each begin their motion of separation at the same instant, and clamping means for securing said unitary structure in position upon said plate. 115

5. In a device of the character described, a mounting plate, a unitary structure detachably located on said plate and comprising a pair of resiliently mounted opposing contact points each movable simultaneously to effect 120 an opening therebetween, a rotatable cam adapted to act upon said contacts to produce such motion thereof, and a binding screw for securing said unitary structure upon said plate, said screw further serving to convey 125 current to one of the contact points.

6. In a device of the character described; a mounting plate; a detachable unitary con-

tact structure located thereon; said structure including a pair of main resilient spring members, a contact on each of said members and normally in closed relation with each other, an extension member fastened to each of said spring members having its end **U**-shaped to receive a wearing element; a cam adapted to pass between said wearing elements to flex said spring members and thereby separate said contacts; and clamping means for securing said contact structure in working position on said mounting plate.

In witness whereof I affix my signature.

SAMUEL C. McKEOWN.
